UNITED STATES PATENT OFFICE.

ALFRED H. SMITH, OF NEW YORK, AND HARRY WANAMAKER, OF ALBANY, NEW YORK.

LOCOMOTIVE ASH-PAN.

1,114,197.

Specification of Letters Patent. Patented Oct. 20, 1914.

Original application filed January 14, 1913, Serial No. 741,995. Divided and this application filed April 21, 1914. Serial No. 833,437.

To all whom it may concern:

Be it known that we, ALFRED H. SMITH and HARRY WANAMAKER, citizens of the United States, and residing, respectively, 5 in the city of New York, State of New York, and city of Albany, State of New York, have invented certain new and useful Improvements in Locomotive Ash-Pans, of which the following is a full, clear, and ex- 10 act description, such as will enable others skilled in the art to which it appertains to make and use the same, reference being had to the accompanying drawings, forming part of this specification, in which—

15 Figure 1 is a side elevational view of an ash pan of our improved construction. Fig. 2 is an end elevation of the ash pan. Fig. 3 is a vertical section taken approximately on the line 3—3 of Fig. 1. Fig. 4 is an en- 20 larged detail sectional view of one of the ash pan door operating mechanisms.

Our invention relates generally to locomotive ash pans, and more particularly to certain novel features of construction of the 25 operating mechanism utilized for opening and closing the drop doors which normally close the opening at the bottom of the pan.

The present application is a division of an application filed by us January 14, 1913, 30 Serial No. 741,995.

Certain types of ash pans now in general use are in the form of hoppers having drop doors hinged so as to swing downward and outward to permit the discharge of the ashes 35 from the ash pan, and it is the primary object of our invention to equip the doors of this type of ash pan with a simple and compact operating mechanism, which can be manipulated with little power to effect the 40 opening and closing movements of said doors.

With the above and other objects in view, our invention consists in certain novel features of construction and arrangement of 45 parts, hereinafter more fully described and claimed.

As shown in the accompanying drawings, the ash pan is in the form of a hopper composed of vertically disposed parallel side walls 10 and inclined end walls 11. Formed integral with or fixed to the lower 50 portions of the walls 10 and on the outer sides thereof are bearings 12 in which are journaled rock shafts 13. Fixed in any suitable manner to these rock shafts are plates 14, the same constituting drop doors 55

for the bottom of the pan, and one of these plates is slightly wider than the other so that its free edge 14a overlaps the corresponding edge of the opposite door. 60

Journaled in suitable bearings 15 at the lower end of one of the end walls 11 is a transversely disposed rock shaft 16, one end of which is extended and provided with a lever 17 by means of which said shaft may 65 be readily rocked. This lever 17 normally rests on a suitable support 18, and if desired, suitable operating connections may be extended from this lever 17 to the interior of the locomotive cab. Fixed on this 70 rock shaft 16 near the bearings 15 are short upwardly projecting levers 19, and pivotally connected to the upper end of each of these levers is a horizontally disposed link 20. These links extend along the sides of 75 the ash pan and their rear ends are pivotally connected to the meeting ends of pairs of vertically disposed toggle links 21. The upper ends of the upper links of each pair are pivotally connected to bearings 22, the 80 same being arranged on fixed portions of the locomotive frame. The lower ends of the lower links are pivotally connected to the outer ends of the short curved arms 23 and the inner ends of these arms are fixed 85 in any suitable manner to the adjacent rock shafts 13. Under normal conditions, or when the doors are closed, as shown in Figs. 2 and 3, the toggle links 21 occupy vertical positions, and the lever 17 rests upon its 90 support 18. To open the doors, the free end of the lever 17 is engaged and raised, thereby rocking shaft 16 and consequently 95 swinging the levers 19 forward into the position shown by dotted lines in Fig. 1. This operation draws the links 20 forward, thereby actuating the toggle links 21, and as the upper end of the upper one of each 100 pair of links operates in fixed bearings, the lower links will be drawn upward as shown by dotted lines in Fig. 1, thereby pulling the outer ends of the curved arms 23 upward, which movement rocks the shafts 13, and consequently swings the doors 14 downward, and outward into the positions shown 105 by dotted lines in Fig. 3.

During the movements just described, the toggle links 21 will swing outward slightly by reason of the change of position of the arms 23, and to permit such outward swinging movement of said links, the upper ends of the upper links have a certain amount of 110

transverse play in the bearings 22, and likewise the lower ends of the lower links are 5 flexibly connected to the outer ends of arms 23. A reverse rocking movement imparted to shaft 16 brings about reverse movement of the parts just described, and as a result, the doors 14 are moved into their normal closed positions with the edge 14^a of one door overlapping the adjacent edge of the 10 opposite door as shown in Fig. 3.

An ash pan door operating mechanism of our improved construction is comparatively simple, is very compact, does not interfere with the free working of any of the operating parts of the locomotive, and by utilizing toggle links and short connections between said links and the doors, said operating mechanism can be manipulated with the expenditure of comparatively little 20 power.

It will be readily understood that minor changes in the size, form and construction of the various parts of our improved locomotive ash pan may be made and substituted for those herein shown and described, without departing from the spirit of our invention, the scope of which is set forth in the appended claims.

We claim:

30 1. The combination with a locomotive ash pan, of shafts journaled on opposite sides of the lower portion of the pan, doors carried by said shafts for closing the opening at the bottom of the pan, crank arms fixed to 35 said shafts, a pair of toggle links arranged between each crank arm and a fixed part of the locomotive frame, the upper ends of the upper links being so connected to the fixed part of the frame as to permit said links to 40 swing longitudinally and transversely with respect to the axis of the pan, the lower ends of the lower links being so connected to the crank arms as to permit said links to swing longitudinally and transversely with respect 45 to the axis of the pan, a rock shaft arranged in suitable bearings adjacent to one end of the ash pan, and connections from said rock shaft to the joints between the toggle links for simultaneously actuating the latter to 50 move the doors.

2. The combination with a locomotive ash pan, of a pair of drop doors hinged to said ash pan for closing the lower end thereof, a 55 pair of toggle links arranged between the central portion of each door and a fixed part of the locomotive frame the upper ends of the upper links and the lower ends of the lower links being so pivotally connected to the doors and the locomotive frame as to 60 permit said links to swing longitudinally and transversely with respect to the axis of the ash pan, and means connected to the joints between the toggle links for simul-

taneously actuating the same to move the doors.

3. The combination with a locomotive ash pan, of a pair of drop doors hinged to the lower portion of the pan for closing the opening in the bottom thereof, crank arms connected to the outer central portions of 70 said doors, toggle links pivotally connected to said crank arms, and to fixed parts of the locomotive frame the upper ends of the upper links and the lower ends of the lower links being so connected to said crank arms 75 and locomotive frame as to permit said links to swing longitudinally and transversely with respect to the axis of the ash pan, and means connected to the joints between said toggle links for actuating the same to move 80 the doors.

4. The combination with a locomotive ash pan, of rock shafts arranged at the sides of the pan near its lower end, doors carried by 85 said shaft for closing the opening at the bottom of the pan, crank arms fixed to said rock shafts near their central portions, toggle links arranged between each crank arm and a fixed part of the locomotive frame the upper ends of the upper links and the lower 90 ends of the lower links being so connected to said crank arms and locomotive frame as to permit said links to swing longitudinally and transversely with respect to the axis of the ash pan, and means connected to each 95 pair of toggle links for simultaneously actuating the same to move the doors.

5. The combination with a locomotive ash pan, of a pair of drop doors hinged to said pan for closing the opening at the lower end 100 thereof, crank arms connected to said doors near their central outer portions, a pair of toggle links between each crank arm and a fixed part of the locomotive frame, the ends of which toggle links are flexibly connected 105 to said crank arms and the fixed parts of the locomotive frame whereby said links can swing simultaneously lengthwise and transversely with respect to the axis of the ash pan, and means connected to the joints between 110 said toggle links for simultaneously actuating the same to move the doors.

In testimony whereof, we have hereunto affixed our signatures in the presence of two subscribing witnesses.
